MARINE FLOAT

Thomas L. Thompson, 310 Fernando, Apt. 102,
Balboa, Calif. 92661

Filed Jan. 19, 1970, Ser. No. 20,993

Term of patent 14 years

Int. Cl. D12—14

U.S. Cl. D71—1

FIG. 1.

FIG. 2.

FIG. 3.

FIG. 4.

FIG. 1 is a top plan view of a marine float embodying my new design;

FIG. 2 is a side-elevational view thereof;

FIG. 3 is an end-elevational view thereof; and

FIG. 4 is an isometric view thereof. The bottom of the float not illustrated has the identical appearance as the top of the float as shown in FIG. 1. The side of the float not illustrated has the identical appearance as the side shown. The end of the float not illustrated has the identical appearance as the end of the float shown.

I claim:

The ornamental design for a marine float, substantially as shown and described.
